UNITED STATES PATENT OFFICE.

GEORGE HAUMANN, OF CLEVELAND, OHIO, ASSIGNOR, BY MESNE ASSIGNMENTS, TO THE URBAN MACHINE AND TOOL COMPANY.

LATHE.

1,417,521.

Specification of Letters Patent. Patented May 30, 1922.

Application filed June 4, 1919. Serial No. 301,761.

To all whom it may concern:

Be it known that I, GEORGE HAUMANN, a former subject of the Emperor of Austria-Hungary, (who has taken out his first papers of citizenship in the United States and has applied for his second papers,) and a resident of Cleveland, county of Cuyahoga, and State of Ohio, have invented a new and useful Improvement in Lathes, of which the following is a specification, the principle of the invention being herein explained and the best mode in which I have contemplated applying that principle, so as to distinguish it from other inventions.

The present improvements relate more particularly to that type of lathe which is designed for handling lighter work than the regular heavy engine lathe. In other words, the present improved lathe is designed to handle work of comparatively short length. The object of the invention is to provide a lathe of this type which will not only be simple and compact, but of sufficiently rigid and substantial construction to enable just as heavy work to be handled thereon, except in the matter of length, as might be handled on the larger lathe. A further object is to insure precision in operation whereby accurate work will be at all times assured. A further object is to combine with a lathe of the type in question a convenient and readily accessible grinder for sharpening tools, such as may be employed on other lathes.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which the principle of the invention may be used.

In said annexed drawings:—

Fig. 1 is a front elevation of my improved lathe; Fig. 2 is a central longitudinal section of the head stock and adja-

cent portion of the bed, as well as of the 50 tool carriage mounted on the latter; Fig. 3 is a transverse section through the head stock and adjacent portion of the bed, showing motor drive for work spindle; and Fig. 4 is an end elevation of such head stock 55 showing arrangement of gears connecting work spindle with feed screw.

The frame or bed of my improved lathe is of extremely simple and yet rigid construction, comprising, as shown in the 60 several figures of the drawings, a main tubular member 1 and supports 2 and 3 for the respective ends of said member. The member 1 comprises simply a section of steel pipe ground exteriorly to true cylindrical form, and formed, preferably on its under side, as mounted in the aforesaid supports 2 and 3, with a longitudinally extending slot 4. The tail-end support 2 is simply a light casting formed with transversely spaced feet 5, while the other support 3, which is formed with similar feet 6, rises above the tubular member 1, is hollow to receive the head stock mechanism presently to be described, and is closed by 75 a removable cover plate 7.

Journalized in suitable bearings 8 and 9, held between the upper face of such hollow support 3 and its cover 7, is the work spindle 10 which may be of any usual construction, such spindle preferably lying directly over the axis of the tubular bed 1 and in alignment with the dead center 11 that is adjustably mounted in the usual manner in a tail stock 12. The latter is 85 itself adjustably mounted on the bed 1, being carried by a split annular base that is slidable on said bed and is adapted to be secured in any desired place longitudinally thereof by a tightening of the clamp screw 90 13 so as to draw its split ends together. A plate 14 held between such split ends projects upwardly into the slot 4 formed in the under side of the bed, so as to hold the tail stock in proper vertical position over the 95 axis of said bed.

Returning to the mechanism in the head stock, a transverse drive shaft 15 will be

noted journaled therein below the spindle 10, said shaft carrying a worm 16 that meshes with a worm gear 17 on a second shaft 18 likewise disposed below work spindle 10 but in parallel relationship therewith. Shaft 15 constitutes in effect the prolongation of the armature spindle of an electric motor 19 (see Fig. 3), disposed to the rear of the head stock and housed in a suitable casing 20 directly attached to the support 3 which constitutes such head stock. The forward end of spindle 15 projects through the front wall of the support 3 and is adapted to receive a grinding wheel 21 or other like device.

Two pairs of change speed gears 22, 23 and 24, 25 are keyed onto shaft 18 so as to be slideable longitudinally thereof through the medium of suitable operating levers 26 and 27 respectively, thus bringing said gears into mesh with corresponding gears 28, 29 and 30, 31 on the work spindle 10. A variety of changes in speed between said work spindle and said shaft 18, or in other words the drive shaft 15, may be thus effected, it being observed that, as shown in Fig. 2, both sets of change speed gears on shaft 18 may be left in neutral, in which event the shaft 15 will run idle, as will be desirable when the grinding wheel 21 is in use. It will further be observed that the bearings for the spindles carrying levers 26 and 27 whereby these change speed gears are shifted, are held between the upper face of head stock 3 and its cover 7, just as are the bearings for the work spindle, thus facilitating the assembly of these parts in the original construction of the machine, or their ready disassembly should it for any reason be afterwards desirable to get access to the interior of the head stock.

The feed screw 35 is centrally supported in the tubular bed 1 having its respective ends journaled in bearings 36 and 37 provided in the corresponding supports 2 and 3 of such bed. The manner in which this screw is operatively connected with the tool slide or carriage 38 is clearly shown in Fig. 2, it being observed that such slide is mounted on a split annular base 39, slidably fitted on the bed 1 and provided with clamp screws 40 whereby its split ends are drawn together. A plate 41 is clamped between such split ends of base 39, and serves not only to hold the carriage in proper vertical position upon the bed 1 by slidably engaging the slot 4 in the latter, but is also formed with an interiorly threaded extension 42 within which the feed screw 35 is threaded. Rotation of the latter, it will accordingly be seen, will serve to move the carriage longitudinally of the bed in either direction, as desired.

For manual rotation of the feed screw 35 a hand-wheel 43 is mounted at the tail end

thereof, which projects beyond the corresponding support 2 with this object in view. For automatic feeding of the carriage, the other end of said feed screw 35 is adapted to be connected with work spindle 10 in the head stock through suitable intermediate gearing (see Fig. 4) such as is regularly employed in lathes. The gearing in question is enclosed in a suitable removable cover 44 attached to the outer end of head stock 3, and comprises a pinion 46 loosely mounted on the projecting end of said shaft 18, which meshes with an intermediate gear 47 which meshes in turn with a large gear 48 on the end of the feed screw 35. The intermediate gear 47 is carried on an arm 49 swiveled about the axis of said screw, and, by substituting gears of different diameters, the screw will be driven to feed the carriage in one direction at varying rates of speed relative to the rate of rotation of the work spindle 10. An idler gear 50 is carried by an arm 51 swiveled about the axis of said shaft 18 so as to enable such gear to be interposed in the gear train between the spindle 10 and the feed screw 35, the effect being obviously to reverse the feed of the carriage.

The tubular bed which forms one of the characteristic features of my improved lathe constitutes an extremely rigid support for the tail stock and carriage, and a high degree of accuracy in the movement of the carriage is insured, since such bed may be readily ground to true cylindrical form. At the same time it provides a convenient housing for the feed screw which is wholly hidden and protected from dirt and injury. The construction of the head stock whereby the various operative parts therein may be readily assembled and disassembled is another extremely convenient feature, quite aside from the direct interconnection of the motor spindle with the intermediate shaft through which the work spindle is driven. At the same time the motor spindle is utilized to carry a grinding wheel in position most convenient to the operator. The compact disposition in the head stock of the change speed gears between the intermediate shaft and the work spindle, as well as the equally compact yet accessible disposition of the change speed gears between the intermediate shaft and the feed screw at the outer end of the head stock, is secured without sacrifice of convenience, but rather the contrary, the operating levers for said change speed gears being all close together and easily manipulated.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:

1. In a lathe, the combination of a slotted tubular member of large diameter and relatively thin material having a cylindrical exterior; supports sleeved upon the respective ends of said member, one of said supports constituting a head-stock change speed gear casing and motor support; a tool-carriage adjustably mounted on said member; a longitudinally disposed work-spindle mounted in said head-stock; a transversely disposed power shaft in said head-stock; a second shaft parallel with said spindle; a worm drive connecting said two shafts; change-speed gearing adapted to connect said second shaft with said spindle; a tool carriage adjustably mounted on said member; a feed-screw extending longitudinally within the latter and operatively connected with said carriage; and change-speed and reverse gearing on the outer end of said head-stock connecting the corresponding ends of said work spindle and screw. 80
2. In a lathe, the combination of a tubular member of large diameter and relatively thin material having a cylindrical exterior and constituting a tool carriage slide and feed screw housing; supports sleeved upon the respective ends of said member, one of said supports constituting a head stock; a tool-carriage adjustably mounted on said member; a longitudinally disposed work-spindle mounted in said head-stock; a transversely disposed drive shaft in said head stock, said shaft projecting beyond the front face of said head-stock to receive a grinding wheel or the like; a second shaft parallel with said spindle; a drive connecting said two shafts; and change-speed gearing adapted to connect said second shaft with said spindle. 95
3. In a lathe, the combination of a tubular member of large diameter and relatively thin material having a cylindrical exterior; supports sleeved upon the respective ends of said member, one of said supports constituting a head-stock; a tool-carriage adjustably mounted on said member; a longitudinally disposed work-spindle mounted in said head-stock; a transversely disposed drive shaft in said head-stock; a second shaft parallel with said spindle; a worm drive connecting said two shafts; change-speed gearing adapted to connect said second shaft with said spindle; a tool-carriage adjustably mounted on said member; a feed-screw extending longitudinally within the latter and operatively connected with said carriage; and change-speed and reverse gearing connecting said work spindle and said screw. 100
4. In a lathe, the combination of a tubular member of large diameter and relatively thin material having a cylindrical exterior; supports sleeved upon the respective ends of said member, one of said supports constituting a head-stock; a tool-carriage adjustably mounted on said member; a longitudinally
5. In a lathe, the combination of a tubular member of large diameter and relatively thin material having a cylindrical exterior; supports sleeved upon the respective ends of said member, one of said supports constituting a head-stock change speed gear casing and motor support; a tool-carriage adjustably mounted on said member; a longitudinally disposed work-spindle mounted in said head-stock; a transversely disposed shaft in said head-stock; a second shaft parallel with said spindle; a worm drive connecting said two shafts; change-speed gearing adapted to connect said second shaft with said spindle; and an electric motor mounted on the rear of said head-stock, said transverse shaft being continuous with the spindle of said motor. 90
6. In a lathe, the combination with a head-stock and work spindle mounted therein; of a transversely disposed shaft below said spindle; a second shaft parallel with said spindle and between the same and said transverse shaft; a worm drive connecting said two shafts; and change-speed gearing adapted to connect said second shaft with said spindle. 105
7. In a lathe, the combination with a head-stock and work spindle mounted therein; of a transversely disposed shaft below said spindle; a second shaft parallel with said spindle and between the same and said transverse shaft; a worm drive connecting said two shafts; change-speed gearing adapted to connect said second shaft with said spindle; and an electric motor mounted on the rear of said head-stock, said transverse shaft being continuous with the spindle of said motor. 110
8. In a lathe, the combination with a head-stock and work spindle mounted therein; of a transversely disposed shaft; a second shaft parallel with said spindle; a drive connecting said two shafts; and change-speed gearing adapted to connect said second shaft with said spindle. 120
9. In a lathe, the combination of a tubular member of large diameter and relatively thin material forming a feed screw housing, tool carriage slide and lathe bed, end 130

supports sleeved upon said member, one end support embodying a longitudinal casing extending above and parallel to one end of said tubular member and reinforced thereby,
5 a work spindle and change speed mechanism contained within said casing and a motor supported upon the rear of said longitudinal casing, a drive shaft from said mo-

tor extending transversely of the longitudinal casing, a feed screw in said tubular member and gearing operatively connecting the mechanism in the longitudinal casing with said motor and that in the tubular member with that in the longitudinal casing. 10

Signed by me, this 2nd day of June, 1919. 15
GEORGE HAUMANN.
